VOLUMETRIC GAS ANALYZERS AND
CONTROL DEVICES

Walter W. Sadler, Davis, Calif.

Application February 2, 1951, Serial No. 209,059

1. Claim. (Cl. 23—256).

1. This invention relates to a means and method for controlling the gaseous exchange of the avian embryo in an incubator.

The principal object of the invention is to provide a device which will automatically and accurately replace gaseous deficiencies in an incubator atmosphere at regular pre-set intervals.

Another object of the invention is to provide means which will automatically analyze the atmosphere at regular intervals and supply any deficiency of desirable gases in direct proportion to the indicated deficiency.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawing:

Fig. 1 is a diagrammatic view illustrating the improved method and means for automatically controlling the gas content of an incubator;

Fig. 2 is a diagram of the electric circuits employed in the improved system; and

Fig. 3 is an enlarged, vertical section through a form of control valve employed in the improved automatic gas supply system.

In Fig. 1, an incubator is indicated at 10, and a gas tank is illustrated at 11. The principal gas necessary to control in an incubator is carbon dioxide, although the control of the oxygen supply is also important.

The improved system will be herein described as supplying carbon dioxide gas to the incubator. The same system, or a duplicate thereof, could be employed for supplying oxygen, as will be later described.

The improved system is designed to supply a gas, such as carbon dioxide, from the tank 11 to the incubator 10 in a direct proportion to the deficiency of this gas in the incubator. This is accomplished by means of three vertically aligned, closed cylinders: an absorbent cylinder 12, a float cylinder 13, and a water cylinder 14. The cylinders 13 and 14 are connected together by means of a below-surface connection 15 and are substantially filled with water, as indicated at 16. For use with carbon dioxide, the absorbent cylinder 12 is filled with sodium hydroxide solution (NaOH) to the level indicated at 17, and the cylinder 12 communicates with the cylinder 14 through an above-surface connection 18.

2. Atmosphere from the incubator 10 is forced into the bottom of the absorbent cylinder 12 through a supply conduit 19 from a pump 20 which draws air from the incubator 10 through a pump supply pipe 21. The pipe 21 is provided with a check valve 22 to prevent the return of air to the incubator 10, and the supply conduit 19 is provided with a similar check valve 23 to prevent the return of air to the pump 20. A piston 24 is reciprocally mounted in the pump 20 and is actuated in any desired manner to periodically complete one cycle of operation.

As illustrated, the pump piston 24 is provided with a piston rod 25 connected through the medium of a connecting rod 26 with a crank pin 27 on a disc gear 28. The gear 28 is driven from an electric motor 29.

The system can be designed to cause the piston 24 to make any desired number of strokes before the current to the motor is cut off. In the system illustrated, the pump 20 is of a size to furnish the required sample of air with one complete stroke of the piston 24, and the motor 29 is automatically stopped upon completion of the one cycle of operation.

This is accomplished by the circuits diagrammed in Fig. 2, in which the operating current is supplied from supply leads 30 and 31. The lead 30 is connected direct to the motor 29. The lead 31 is connected to a motor switch 32 which is closed by means of a cam 33 actuated from an electric clock 34. A motor conductor 35 leads from the motor switch 32 to the motor 29.

A circuit-holding cam 36 is mounted on a shaft 37, upon which the disc gear 28 is mounted, so as to rotate with the latter. A circuit-holding switch 38 is arranged to be opened by the cam 36 and is bridged across the switch 32 by means of conductors 39.

Thus, it can be seen that at pre-set time intervals the cam 33 will close the motor switch 32. This will start the motor 29, causing the holding cam 36 to rotate and the piston 24 to draw air from the incubator 10. The clock cam 33 will now open the switch 32, but the circuit will be held closed by the holding switch 38 which closes when the cam 36 starts to rotate. The circuit will remain closed until the pump piston finishes its cycle, at which time the holding switch 38 will be opened by the cam 36.

The size of the pump 20 is designed to displace a predetermined sample quantity of air. This sample quantity is forced through the pipe 19 to the absorbent cylinder 12, where it bubbles upwardly through the sodium hydroxide therein to increase the pressure in the upper portion of

the cylinder 12. This pressure is transferred to the water cylinder 14, where it acts to depress the water therein, forcing the latter into the float cylinder 13, thus resulting in a lower water level in the cylinder 14 and a higher water level in the cylinder 13. This variation in water level in the cylinder 13 is employed to raise and lower a float 40, which is slidably mounted in a float chamber 41 mounted on top of the float cylinder 13.

The movements of the float 40 are transmitted by means of a float rod 42 to a gas regulating valve 43. The valve 43 is placed in a carbon dioxide line 44 leading from the carbon dioxide tank 11 to the incubator 10. The regulating valve 43 is provided with a graduated valve member of any design which will allow gas to flow in direct proportion to the amount of lift of the valve. As illustrated, it comprises an inverted, graduated cone 45 which at its largest diameter completely closes a valve seat 46 and gradually opens the seat, in correspondence to the incline of the cone, as the cone is elevated.

Let us assume that the pump piston 24 makes one complete cycle so as to draw a measured sample of atmosphere from the incubator 10 into the pump and force the latter sample into the absorbent cylinder 12. The carbon dioxide content in the atmosphere will be absorbed in the sodium hydroxide 17, allowing the remainder of the atmosphere to bubble from the top of the solution. Naturally, the greater the carbon dioxide content of the sample, the less will be the amount of atmosphere bubbling from the top of the sodium hydroxide. Therefore, the amount of air in the top of the cylinders 12 and 14 will be in inverse proportion to the carbon dioxide content of the sample.

The pressure created by the residual atmosphere will cause the water in the cylinder 13 to rise so as to lift the float 40 and the valve member 45 in inverse proportion to the carbon dioxide content within the sample. For instance, should there not be any carbon dioxide in the sample, the full cubic contents of the sample will be imposed upon the water in the cylinder 14 so as to raise the water in the cylinder 13 to its maximum point, thus admitting a maximum amount of carbon dioxide to the incubator. Should the sample consist of substantially all carbon dioxide, the latter will be absorbed in the absorbent cylinder 12 so that no pressure will be created on the water and the valve member 45 will not open.

Means must be provided for restoring the system to normal after the sample has been analyzed and gas deficiency corrected. This may be accomplished in many ways, either mechanically or electrically. As illustrated, an exhaust pipe 47 is placed at the top of the cylinder 12 and controlled by a solenoid valve 48. The solenoid of the valve 48 is connected to the supply lead 30 by a conductor 49, and to the lead 31 through a second conductor 50 in series with which a valve switch 51 is placed. The switch 51 is positioned to be closed by the cam 36, or by a separate cam on the same cam shaft, slightly in advance of the opening of the switch 38.

Therefore, it can be seen that at the completion of the sampling, the solenoid valve will be opened to allow the air under pressure of the water head in the float cylinder to escape so as to lower the float and close the valve member 45 to await the next impulse from the clock 34.

While the system has been described as relating to carbon dioxide, it could be used on any other gas capable of being absorbed in a liquid absorbent in the absorbent cylinder 12. For instance, should it be desired to control the oxygen content in the incubator as well as the carbon dioxide, the cylinders 12, 13, and 14 would be repeated to control a second valve 43 in an oxygen line feeding the incubator. The second absorbent cylinder would contain pyrogallic acid for absorbing the oxygen from the sample received from the pump 26.

Should it be desired to delay the opening of the exhaust valve for a period after the stopping of the motor, it would be within the skill of any electrician to place a delayed relay in series with the conductor 49 or 50 to control the current supply to the solenoid valve.

Funnels 52 and filling valves 53 are provided for filling the cylinders 12, 13, and 14, and drain cocks 54 are provided for draining these cylinders so that the desired fluid levels may be attained therein.

While a specific form of the improvement has been described and illustrated herein, it is to be understood that the same may be varied, within the scope of the appended claim, without departing from the spirit of the invention.

Having thus described the invention, what is claimed and desired secured by Letters Patent is:

An apparatus for controlling the supply of a predetermined gas to an incubator comprising: a pump having an inlet pipe connected with the incubator; a check valve in said inlet pipe preventing flow from said pump; a vertically disposed absorbent tank adapted to contain a liquid absorbent for the said gas; a pressure conduit connecting said pump to the lower portion of said absorbent tank; a check valve in said pressure conduit preventing return flow to said pump; a pair of water cylinders disposed vertically adjacent said absorbent tank and interconnected adjacent their lower ends and adapted to contain water; an unobstructed connecting pipe communicating between the upper portion of said absorbent tank and the upper portion of the first of said pair of cylinders; a vertically-disposed, open-ended float chamber extending upwardly from the top of the second of said pair of cylinders; a float movable vertically in said second cylinder and extending upwardly therefrom into said float chamber; a stem extending upwardly from said float through the float chamber and outwardly through the upper end thereof; a storage tank for gas; a gas pipe connecting the storage tank to the incubator; a valve in said gas pipe, which valve includes a casing having a horizontal partition formed with an opening, and a closure for the opening shiftable vertically to opened and closed positions; and a stem extending from said closure through the bottom of said casing and being connected with the stem of said float whereby the closure is shifted to the opened and closed positions in response to the vertical movements of the float.
